(57) **CLAIM**

The ornamental design for a perimeter seismic slip joint clip, as shown and described.

DESCRIPTION

FIG. 1 is an isometric view of the perimeter seismic slip joint clip;

FIG. 2 is a top plan view of the clip;

FIG. 3 is a left side elevational view of the clip, the right side view being a mirror image thereof;

FIG. 4 is a bottom plan view of the clip;

FIG. 5 is a front elevational view of the clip; and,

FIG. 6 is a rear elevational view of the clip.
